UNITED STATES PATENT OFFICE

107,856

DESIGN FOR INSULATED WIRE

Clarence A. Farrar, Whitman, Mass.

Application September 11, 1936, Serial No. 64,803

Term of patent 14 years

To all whom it may concern:

Be it known that I, Clarence A. Farrar, a citizen of the United States, residing at Whitman in the county of Plymouth and State of Massachusetts, have invented a new, original, and ornamental Design for Insulated Wire, of which the following is a specification, reference being had to the accompanying drawing, forming part thereof.

The figure is a plan view of a piece of insulated wire showing my new design.

The ornamentation shown on the side illustrated in the drawing figure is continued around the insulated wire covering.

I claim:

The ornamental design for insulated wire as shown and described.

CLARENCE A. FARRAR.
